J. OAKLEY ET AL.

BROACH MECHANISM

Filed April 2, 1927

UNITED STATES PATENT OFFICE.

JOHN OAKLEY AND HIRAM D. CROFT, OF SPRINGFIELD, MASSACHUSETTS, ASSIGNEES
TO PERKINS MACHINE AND GEAR COMPANY, OF SPRINGFIELD, MASSACHUSETTS, A
CORPORATION OF MASSACHUSETTS.

BROACH MECHANISM.

Application filed April 2, 1927. Serial No. 180,380.

Our invention relates to improvements in mechanisms for automatically changing the positions of reciprocating broaches, and consists generally of means for holding broaches, 5 means for pivotally attaching said first-named means to a reciprocating member in such a manner that said holding means can be moved through an arc to locate the broaches carried thereby alternately in a 10 vertical plane or in the cutting field, means automatically to swing said first-named means each time said member approaches either end of its travel, and means to lock and release said first-named means each time one 15 of said broaches is positioned in the cutting field, together with such other parts and members as may be necessary or desirable in order to render the mechanism complete and serviceable in every respect, all as hereinafter 20 set forth.

The primary object of our invention is to provide comparatively simple, yet strong, durable, and highly efficient, mechanism for automatically swinging first in one direction 25 and then in the other, from an axis common to both, two broaches or two lines of broaches to locate them alternately or one after the other in the cutting field or broaching position, to the end that the cutting or broaching 30 operation is practically continuous, that is to say, when the two broaches or two lines of broaches descend one of them makes a cut, and when they ascend the other makes a cut, 35 and the operation of broaching is thereby materially accelerated, and the production of the machine equipped with our mechanism correspondingly increased.

Another object is to produce a mechanism of this character which is positive and accurate in its operation.

Other objects and advantages will appear in the course of the following description.

This mechanism is designed to be incorporated with broaching machines of the type 45 disclosed in Letters Patent of the United States, No. 1,642,593.

We attain the objects and secure the advantages of our invention, by the mechanism illustrated in the accompanying drawings, 50 in which—

Figure 1 is a top plan of broach mechanism which embodies a practical form of our invention, showing the same in connection with

the closely associated parts and members of a broaching machine, and with certain portions 55 broken out; Fig. 2, a crosssection through portions of said mechanism and said parts and members, taken on lines 2—2, looking down, in Fig. 4; Fig. 3, a left-hand side elevation of said mechanism and said parts and members, 60 with portions broken out and broken away; Fig. 4, a front elevation of said mechanism, or enough of the same to show its disposition when the broaches are at the upper end of their travel; Fig. 5, a similar view showing the disposition of said mechanism when 65 said broaches are at the lower end of their travel, and, Fig. 6, a detail in front elevation of the locking device for the broach holder.

Similar reference characters designate similar parts throughout the several views.

The old parts and members shown in connection herewith as necessary for a complete understanding of the present invention comprise a column 1, a ram 3 arranged to reciprocate vertically on said column, and provided on one side with a rack 4, and a pinion 5 intermeshing with said rack, said pinion being mounted on a shaft 6. From any suitable source of motive power the shaft 6 is 75 caused to rotate, and, through the medium of the pinion 5 and the rack 4, to actuate the ram 3 on the column 1. Reversing means for the shaft 6, and means to bring about the operation of said reversing means each time the 80 ram arrives at either end of its travel, are required, but these are not shown because the nature of the same is well understood. In 85 this connection, however, reference may be had to the aforesaid application, Serial No. 90 80,326.

Broaches such as are used in this art are usually made up in sections arranged end to end, so that the separate sections or individual broaches, to all intents and purposes, 95 form one broach, and, they will herein be so considered. Two broaches of this character are represented at 7 and 8, respectively, the broach 7 being at the left and the broach 8 at the right. The broach 7 cuts on the down 100 stroke and the broach 8 cuts on the up stroke.

A holder 9, in the form of a sector, is provided for the broaches 7 and 8. The holder 9 is arranged with its apex at the top, where said holder is mounted to swing on a bolt 10 105 that projects from the face of the ram 3 in

the longitudinal center thereof. Two nuts 11 are threaded onto the forward end of the bolt 10, outside of the part of the holder 9 that is mounted on said bolt, to prevent the 5 same from becoming displaced. A washer 56 is interposed between the axial part of the holder and rear nut 11. To serve as means to guide the holder 9 at the bottom, and assist in supporting, and in retaining said holder 10 against the face of the ram 3, are two segmental blocks 12 secured by bolts or other means to said ram, and spaced apart in the longitudinal center of the ram. The bottom edge of the holder 9, which edge is arcuate, 15 has two notches 13 therein located a short distance in from the ends of said edge. Those portions of the arcuate edge of the holder 9, which are at the sides of the notches 13, are beveled from above downward and rearward, 20 as represented at 14, and the upper edges of the blocks are correspondingly beveled. These beveled parts are in contiguity, and the base of the holder is thereby supported and held against the face of the ram, but at 25 the same time permitted to slide as said holder is swung on its pivot. If desired additional supporting and guiding means for the holder 9 may be provided in the form of arcuate bars secured by screws or other means 30 to the ram 3, said bars being let into arcuate slots in the face of said ram and projecting forwardly into arcuate slots in the back side of said holder. In the present example there is an arcuate bar 15 below the pivot bolt 10, 35 and two arcuate bars 16 above the base of the holder 9, said last-named bars being spaced apart in the longitudinal center of the ram. The bars 15 and 16 and the blocks 12, are, of course, concentric with the bottom edge of 40 the holder 9.

In the front side of the holder 9 are two radial slots 17 and a recess 18 having radial sides, into which recess said slots open at their upper ends. The bodies of the broaches 45 7 and 8, each of which bodies in cross section is dove-tail in form, are received in the slots 17 and the recess 18. The outer sides of the aforesaid slots and both sides of the aforesaid recess are cut to correspond with the 50 outer inclined sides of the bodies of the broaches 7 and 8. A wedge block 19 is received in the recess 18, and two radial wedge bars 20 are received in the slots 17. The sides of the wedge block 19 and the outer sides of 55 the wedge bars 20 are inclined to correspond with the inner inclined sides of the broaches 7 and 8, but the inner edges of said wedge bars are perpendicular to the front and back sides thereof. The wedge block 19 and the 60 wedge bars 20 are secured by screws or other means to the holder 9. An abutment block 21 is interposed between the upper ends of the broaches 7 and 8 and wedge block 19 below and the top of the recess 18 above, and 65 an abutment block 22 is interposed in each

slot 17 between the lower end of the broach in said slot and the bottom of the slot, any suitable means being employed to fasten said blocks in place. Thus it is seen that the two broaches are rigidly secured in, with their 70 teeth projecting beyond, the holder 9.

In the present construction, when either broach 7 or 8 is disposed vertically, it is in position to make its cut, or, in other words, 75

There are two horizontal slots 23 and 24 in the face of the ram 3. These slots are between the guide bars 15 and 16. In the back side of the holder 9 is an annular recess 25, and below that an arcuate recess 26. There is also an annular recess 27 in the face of the ram 3 directly behind the recess 25 in the holder 9 and of the same size. A rack bar 28 and a plunger-operating bar 29 are slidingly arranged in the slots 23 and 24, respectively, 80 each of said bars adjacent to its left-hand terminal having therein a longitudinal slot 30 to receive a screw 31 which passes through said slot to be tapped into the ram 3. The screws 31 are countersunk in the slotted parts of the bars 28 and 29 and assist in retaining said bars in the slots 23 and 24. The rack bar 28 extends beyond the left-hand side of the ram, and is provided at the outer terminal on the back side with a roll 32. The bar 29 also extends beyond the left-hand side of the ram, and there has an upwardly-extending arm 33 which is provided at the upper end on the back side with a roll 34. The roll 34 is wider than the roll 32. 85

An upright 35 is located at the left of the ram 3, and has at the top a rearwardly-extending flange 36 that is bolted at 37 to a fixed part 38 of the frame of the machine, and has its lower terminal bolted, as at 39, to a fixed 90 part 40 of said frame. Secured by screws or other means to the front side of the upright 35, near the upper end thereof, is a cam block 41 having two inclined cam surfaces 42 and 43, the upper of said surfaces projecting forwardly beyond the lower of said surfaces. The cam surface 43 is at the bottom of the block 41. The cam surfaces 42 and 43 are 95 parallel with each other and incline from below upwardly and to the left. A second cam block 44 is secured by screws or other means to the front side near the lower end of the upright 35, and this block has at the top an inclined cam surface 45 which is parallel with the cam surfaces 42 and 43. The cam block 44 is set farther to the left on the upright 35 than is the cam block 41. The rolls 32 and 34 are 100 in position to engage the cam blocks 41 and 44 and thereby to actuate the rack bar 28 and the plunger-operating bar 29, as will herein-after be more fully explained. The cam block 44 is of the same thickness as the cam block 41 in its thickest part. 105

On the bottom of the bar 28 are teeth 46, and on the bottom of the bar 29 is a projec- 110

120

125

130

tion having downwardly convergent ends to form a dog 47.

Let into the arcuate recess 26 in the back side of the holder 9 is a toothed segment 48, the teeth being on the upper, convex edge of said segment. A stud 49 projects forwardly from the ram 3 into the center of the recess 27 therein, and a pinion 50 is loosely mounted on said stud. The pinion 50 intermeshes 10 with the teeth on the rack bar 28 above, and with the teeth on the segment 48 below. The segment 48 is concentric with the other arcuate members.

Obviously, if the rack bar 28 be moved to 15 the right, from the position which it occupies in Fig. 4, it will impart, through the medium of the pinion 50, a motion to the segment 48 which carries the latter to the left and thereby causes the holder 9 to be swung on its pivot 20 10 in the same direction, and, if said bar be moved to the left, from the position which it occupies in Fig. 5, it will impart, through the medium of said pinion, a motion to said segment which carries the latter to the right and 25 thereby causes said holder to be swung on said pivot in the same direction.

On the front of the ram 3, at the bottom and in the longitudinal center of said ram, is a vertical socket 51 closed at the bottom by 30 means of a screw plug 52, and in which is a spring 53. A latch 54 is located in the space between the adjacent ends of the guide-blocks 12, and pinned to said latch behind the same is a vertical tongue or plunger 55 beveled at 35 the upper terminal to correspond with the beveled ends of the dog 47. The plunger 55 rests on the spring 53, which latter normally retains said plunger and the latch 54 in elevated position. The upper end of the latch 40 54 is adapted to enter either of the notches 13 in the bottom of the holder 9, and to lock said holder with either the broach 7 or the broach 8 in the cutting field, accordingly as 45 said latch is in the left-hand or the right-hand notch. The plunger 55 extends upwardly through the space between the adjacent ends of the guide bars 16 to bear against the under side of the bar 29 or of the dog 47. Normally 50 the plunger bears against the under side of the bar itself and is in contiguity with one end or the other of the dog 47.

When the bar 29 is actuated to the right, from the position which it occupies in Fig. 4, the dog 47 forces the plunger 55 downwardly, 55 against the resiliency of the spring 53, and thus removes the latch 54 from the left-hand notch 13. As soon as the dog 47 passes the top of the plunger 55, the spring 53 causes said plunger to be elevated into position at 60 the left of said dog, and thus to raise the latch 54 into the right-hand notch 13, said notch having been positioned to receive said latch by the movement of the holder 9 when swung to the left. Then, when the bar 29 is actuated 65 to the left, from the position which it occu-

pies in Fig. 5, the dog 47 forces the plunger 55 downwardly a second time to withdraw the latch 54 from engagement with the holder, said latch subsequently reengaging said holder and locking it in the first position 70 again.

Starting with the parts disposed as in Figs. 1, 2, 3, 4, and 6, the operation of the mechanism as a whole is described as follows:

Upon the descent of the ram 3 to make a 75 cut with the broach 7, the bars 28 and 29 are carried downwardly. In descending the roll 34 carried by the bar 29 encounters the cam surface 45 of the cam plate 44, after the broach 7 has made its cut, and said bar is 80 thereby actuated to the right far enough to cause the latch 54 to be removed from the right-hand notch 13, through the medium of the dog 47 and the plunger 55. The roll 34 finally passes down against the right-hand 85 edge of the cam plate 44, when the bar 29 is so disposed that the left-hand end of the dog 47 is in position to receive against it the adjacent beveled edge at the top of the plunger 55. Meanwhile the roll 32 encounters the cam 90 surface 45 of the cam plate 44, and actuates the rack bar 28 to the right, with the result that the holder 9, through the medium of the pinion 50 and the segment 48, is swung to the left, and the broach 7 is removed and the 95 broach 8 is positioned in the cutting field. As soon as the roll 32 rides off of the cam surface 45 and down against the right-hand edge of the cam plate 44, the latch 54, which was 100 released to the spring 53 as soon as the dog 47 cleared the plunger 55, and is now bearing on the under edge of the holder 9, rises into the right-hand slot 13 and locks the holder with the broach 8 in active position. Next the driving mechanism for the ram 3 is 105 reversed and said ram ascends to make a cut with the broach 8. The ascending roll 34 encounters the cam surface 43 of the cam plate 41, and causes the bar 29 to be actuated to the left again and the holder 9 to be a second 110 time unlocked. Directly after the holder 9 is unlocked the roll 32 encounters the cam surface 42, of the cam plate 41, and causes the bar 28 to be actuated to the left again with the result that said holder is swung to the 115 right to remove the broach 8 from and locate the broach 7 a second time in the cutting field. The movement to the left of the bar 29 relocates the dog 47 at the left of the plunger 55, in position ready to act on said plunger 120 again when said bar is a second time actuated to the right, and the latch 54 enters the left-hand notch 13 to lock the holder. The rolls 34 and 32 have now passed off of the respective cam surfaces 43 and 42, and up against 125 the left-hand side of the cam plate 41. Next the direction of the driving mechanism for the ram is a second time reversed and said ram descends to make the second cut with the broach 7. These operations are repeated 130

as the ram moves up and down, and first one broach and then the other broach makes its cut, so long as the machine is in motion.

By changing the wedge bars 20, the wedge block 19, and the abutment blocks 21 and 22, broaches of different lengths and sizes can be substituted for the broaches 7 and 8.

More or less change in the shape, size, construction, and arrangement of some or all of the parts of this mechanism may be made without departing from the spirit of our invention or exceeding the scope of what is claimed.

What we claim as our invention, and desire to secure by Letters Patent, is—

1. In mechanism of the class described, a reciprocating member, a holder, means to support said holder from and in front of one face of said member and permit the holder to swing, on a point of suspension transverse to said holder, in a plane parallel with said face, said holder being for broaches arranged therein radially in the direction of their length to said supporting means, and adapted to cut alternately when moved in opposite directions with said member, and means automatically to swing said holder, first in one and then in the other direction, as said member approaches the ends of its travel, to locate one broach in cutting position and the other broach at an angle thereto, and then to locate the second broach in cutting position and the first broach at an angle thereto.

2. The combination, in mechanism of the class described, with a reciprocating member provided with a horizontal pivot, of a holder mounted to swing on said pivot in a vertical plane, said holder being for lengthwise radial broaches, and independently movable relative to said member, and means automatically to change the position of said holder, each time said member approaches either end of its travel, to locate one of said broaches vertically in cutting position and the other at an angle thereto, and then to locate the second broach vertically in cutting position and the first broach in angular relation thereto.

3. The combination, in mechanism of the class described, with a reciprocating member provided with a horizontal pivot, of a holder mounted to swing in a vertical plane of said pivot, said holder being for lengthwise radial broaches, and capable of independent movement relative to said member, means automatically to change the position of said holder, each time said member approaches either end of its travel, to locate one of said broaches vertically in cutting position and the other in angular relation thereto, and then to locate the second broach vertically in cutting position and the first broach in angular relation thereto, and means automatically to lock said holder when disposed with either broach in vertical position, and to release the same after the cut has been made.

4. The combination, in mechanism of the class described, with a reciprocating member provided with a pivot, and with guide means, of a holder for broaches adapted to cut alternately as said member reciprocates, mounted at the top on said pivot and guided at the bottom by said means, and automatic means to cause said holder to be swung on said pivot each time said reciprocating member approaches either end of its travel.

5. The combination, in mechanism of the class described, with a reciprocating member provided with a pivot, and with guide means, of a holder for broaches adapted to cut alternately as said member reciprocates, mounted at the top on said pivot and guided at the bottom by said means, automatic means to cause said holder to be swung on its pivot each time said reciprocating member approaches either end of its travel, and means automatically to lock said holder when disposed with either of said broaches in the cutting field, and to release the same after the cut is made.

6. The combination, in mechanism of the class described, with a reciprocating member, a rack bar transversely arranged in said member, and provided with a projection, and a pinion carried by said member and intermeshing with the teeth of said bar, of a holder, for radial broaches adapted to cut alternately as said member reciprocates, pivotally connected therewith, and provided with a serrated segment intermeshing with said pinion, and cam blocks arranged in the path of said projection to cause said bar to be actuated in opposite directions as said reciprocating member approaches the ends of its travel.

7. The combination, in mechanism of the class described, with a reciprocating member, a rack bar and a plunger-actuating bar slidably arranged laterally in said member, and provided at their outer ends with projections, said second-named bar also being provided with a dog, and a pinion carried by said reciprocating member and intermeshing with the teeth of said rack bar, of a holder, for radial broaches adapted to cut alternately as said member reciprocates, pivotally connected therewith, and having notches in the bottom edge thereof, a segment secured to said holder and having teeth which intermesh with said pinion, a latch carried by said reciprocating member in position to enter either of the notches in said holder, a plunger extending from said latch into the path of said dog, a spring arranged normally to retain said plunger in the path of said dog and said latch in one or the other of said notches, and cam blocks in the paths of said projections to cause said plunger-actuating bar and said rack bar to be moved sequentially as said reciprocating member approaches either end of its travel.

8. The combination, in mechanism of the class described, with a reciprocating member, a rack bar and a plunger-actuating bar slidingly arranged laterally in said member, and provided at their outer ends with projections, said second-named bar also being provided with a dog, and a pinion carried by said reciprocating member and intermeshing with the teeth of said rack bar, of a holder, for radial broaches adapted to cut alternately as said member reciprocates, pivotally connected therewith, and having notches in the bottom edge thereof, a segment secured to said holder and having teeth which intermesh with said pinion, a latch carried by said reciprocating member in position to enter either of the notches in said holder, a plunger ex-

tending from said latch into the path of said dog, a spring arranged normally to retain said plunger in the path of said dog and said latch in one or the other of said notches, a cam block in the path of said projections, when they descend, adapted to cause said plunger-actuating and rack bars to be sequentially moved inwardly, and a cam plate having two cam surfaces in the paths of said projections, when they ascend, adapted to cause said bars to be sequentially moved outwardly, said plunger-actuated bar each time being moved to cause said latch to release said holder, before said rack bar commences to move to change the position of said holder. 20 25 30
